UNITED STATES PATENT OFFICE.

CLAYTON G. WHITE, OF DETROIT, MICHIGAN.

ELECTRIC SWITCH.

1,114,831.

Specification of Letters Patent. Patented Oct. 27, 1914.

Application filed February 2, 1914. Serial No. 816,018.

To all whom it may concern:

Be it known that I, CLAYTON G. WHITE, a citizen of the United States, residing at Detroit, in the county of Wayne and State of Michigan, have invented certain new and useful Improvements in Electric Switches; and I do declare the following to be a full, clear, and exact description of the invention, such as will enable others skilled in the art 10 to which it appertains to make and use the same.

This invention relates to improvements in electric switches and more particularly to those which are provided with indicating 15 dials and fingers which must be moved to predetermined positions in order to complete the electric circuit.

The primary object of the invention is to provide a device of this character which will 20 be simple, strong and efficient in operation and readily adapted to the purpose for which it is designed.

A secondary object is to provide means whereby a great number of entirely different 25 combinations may be used for operating the same switch. This feature will enable the device to be constructed in one form which may be used in a great number of places, each one of said devices having an 30 entirely different combination.

With the above objects in view, the invention resides in certain novel features of construction and combination herein described and claimed and shown in the drawings 35 wherein:—

Figure 1 is a front elevation of my improved switch; Fig. 2 is a plan view thereof; Fig. 3 is a vertical section on the line 3—3 of Fig. 6; Fig. 4 is a rear elevation; Fig. 5 40 is a horizontal section on the line 5—5 of Fig. 1; and Fig. 6 is a transverse section on the line 6—6 of Fig. 3.

In the accompanying drawings, I have shown a casing 1 which is preferably rectangular and is provided with forwardly 45 projecting lugs 2 on its top 3, bottom 4, and end walls 5, said lugs normally projecting through slots in a face plate 6 and being upset to retain said plate in position. The 50 back plate 7 of the casing 1 and the face plate 6 are provided with alined bearing openings 8 in which are revolvably journaled the outer and inner reduced ends 9 and 9' of hollow drums 10. The bores of the drums 55 10 extend throughout their entire length and

are closed, at their forward ends, by operating disks 11 which are provided with flanges 12 which project into said bores. Locking pins 13 are inserted through the drums 10 and the flanges 12 for keying the same together. The inner ends of the drums 10 are internally threaded for the reception of nuts 14 which are provided with circular openings in their centers for a purpose to appear. 60

Each drum 10 is provided with a plurality of longitudinal grooves 15 in its periphery and with openings 16, extending from said grooves into the bores of said drums. The grooves 15 are provided for the reception 70 of contact plates 17 through which and the openings 16, pass screws 18, the latter being threaded into sockets 19 formed integrally with L-shaped arms 20 which carry rigid bearing balls 21 on their free ends. 75 The balls 21 form one member of a swiveled connection between the arms 20 and binding posts 22 which pass loosely through the openings in the nuts 14, the other member of each swiveled connection being in the 80 form of a socket 23 carried rigidly by the inner end of each binding post 22. In other words, the connections between the binding posts 22 and the arms 20 are ball and socket joints and as shown, said joints are disposed 85 in the centers of the drums 10. Each binding post 22 is provided with a suitable longitudinal bore in which its respective current conducting wire is adapted to be inserted and secured by a set screw 24. 90

Contacting with the peripheries of the drums 10 are contact balls 25 which are revolvably mounted between curved fingers 26, depending rigidly from resilient arms 27 which are electrically connected to the inner 95 ends of binding posts 28, the latter extending through the top 3 of the casing 1 and being insulated therefrom.

It has been stated that the grooves 15 are designed for the reception of the contact plates 17. They are however, designed for a second purpose also, since, when the drums 10 are turned by their operating disks 11, the resiliency of the arms 27 will force the balls 25 into said grooves and will thus form 100 a frictional lock for holding the drums 10 in any one of their numerous positions.

One of the disks 11 is provided with an annular series of figures ranging from 1 to 10 while the other disk is provided with an 110

annular series of letters. The number of figures or letters on the disks 11 will be the same as the number of grooves 15 in their respective drums 10. The figures and letters are adapted to co-act with suitable indicators 29 on the face plate 6.

In the operation of the device, assuming that the contact plates 17 are positioned in certain of the grooves 15 and that when in this position, the numeral 1 will register with one of the indicators 29 while the letter A will register with the other indicator, the circuit will be completed and the current will flow through the binding posts 22, the arms 20, the screws 18, the contact plates 17, the balls and arms 25 and 27 and lastly through the binding posts 28 from which it may be conducted by suitable wires connected thereto. When it is desired to break the current, it is simply necessary to rotate the disks 11 which will of course move the plates 17 out of contact with the balls 25. If the combination of the switch is not known, various attempts may be made to complete the circuit by rotating the disks 11 but the attempt will be futile since but one combination (1—A, known only by the legitimate operator) will complete the circuit, it being understood that the switch mechanism, at each end of the casing, is included within the circuit to be completed. It is possible of course, that various attempts might have the desired result, but it is highly improbable.

From the foregoing description and the illustration in the drawings, it will be readily understood that a great number of combinations may be obtained by simply removing the screws 18 whereupon the plates 17 may be located in other grooves 15 and said screws again inserted through said plates and certain of the openings 16 into their sockets 19. The great number of combinations to be thus obtained, render my invention particularly adaptable for use in connection with automobiles and motor boats since, as above stated, it will be practically impossible for any unauthorized person to complete the circuit which operates the sparking mechanism as is readily understood.

Having thus described my invention, what I claim as new and desire to secure by Letters Patent is:

1. An electric switch comprising a casing, a plurality of hollow cylindrical drums revolvably mounted therein, a contact point on the periphery of each of said drums, a rigidly held binding post projecting into the bore of each of said drums, a swiveled connection between said binding posts and said contact points, contact arms bearing yieldingly upon the peripheries of said drums and external means for rotating said drums and for determining the position of said

contact points in respect to said contact arms.

2. An electric switch comprising a casing, a plurality of hollow cylindrical drums revolvably mounted therein, each of said drums 70 having a transverse groove in its periphery, a contact plate in each of said grooves, a rigidly held binding post projecting into the bore of each drum at the center thereof, an arm projecting radially inward from 75 each contact plate and having a revoluble connection with the binding post within the drum in which it projects, contact arms frictionally engaged with the peripheries of said drums, and external means for determining the positioning of said contact plates in respect to said contact arms.

3. An electric switch comprising a casing, a plurality of hollow cylindrical drums revolvably mounted therein and provided with 85 transverse grooves in their peripheries and with openings extending from said grooves into their bores, a contact plate removably seated in one of the grooves of each of said drums, rigidly held binding posts projecting into the bores of said drums and each carrying a bearing journal revolvably connected to its inner end, screws passing through said contact plates and said openings and into said bearing journals, contact 95 arms supported by said casing and bearing yieldingly upon the peripheries of said drums and external means for rotating said drums and for determining the positioning of said contact plates in respect to said contact arms.

4. An electric switch comprising a casing, a plurality of hollow cylindrical drums revolvably mounted therein, rigidly held binding posts projecting into the bores of said 105 drums and each carrying a bearing journal revolvably connected to its inner end, contact screws passing through the walls of said drums and threaded into said bearing journals, contact arms carried by said casing and in frictional contact with the peripheries of said drums and external means for rotating said drums and for determining the positioning of said contact screws in respect to said contact arms.

5. An electrical switch comprising a casing, a hollow cylindrical drum revolvably mounted therein, a contact point on the periphery of said drum, a rigidly held binding post projecting into the bore of said 110 drum, a swiveled connection between said binding post and said contact point, a contact arm bearing yieldingly upon the periphery of said drum and external means for determining the position of said contact point in respect to said contact arm.

6. An electrical switch comprising a casing, a hollow cylindrical drum revolvably mounted therein, a contact point on the periphery of said drum, a rigidly held bind-

ing post projecting into the bore of said drum, a swiveled connection between said binding post and said contact point, a contact arm bearing yieldingly upon the periphery of said drum and means for rotating said drum to close the circuit. In testimony whereof I have hereunto set my hand in presence of two subscribing witnesses.
